APPARATUS FOR THE PRODUCING OF AQUEOUS SUSPENSIONS OF CLAY

Holger Brudal, Strand, Baerum, near Oslo, Norway; vested in the Alien Property Custodian

Application December 9, 1939, Serial No. 308,484
In Norway December 10, 1938

2 Claims. (Cl. 83—6)

This invention relates to the producing of aqueous suspensions of clay. The invention is more particularly concerned with the producing of clay suspensions especially adapted for use as a binding agent for the stabilisation of gravel road surfaces and bases.

For this purpose clay is usually added to the gravel, the gravel and the clay being mixed in special machines. In the mixture thereby obtained, the clay usually appears as more or less rich clay slices or lumps. The purpose of the clay in the stabilised gravel road surfaces is, however, to impart internal cohesion to the gravel mass. In order to fulfill this purpose even the finest particles of the gravel must be coated by a thin film of clay, a purpose which is completely attainable only if the clay is brought into a completely liquid state, as an aqueous suspension wherein the clay is evenly distributed as the finest possible particles.

According to the present invention such finely suspended clay is obtained by cutting the clay into extremely thin slices and small particles by means of a quickly rotating knife device, water being supplied to the clay during the cutting. Preferably a jet of water is directed against the knife device.

The clay to be treated preferably is fed to the knife device from a container through an outlet in the same, in close proximity to which the knife device is located, the clay being forced through the said opening by means of a suitable feeding device. The feeding device may be of any convenient construction. It may be a rotary device comprising feeding screw or screws, if desired combined with pug mill knives or the device may comprise feeding pistons or the like and be arranged with its axis horizontal, vertical or inclined.

In some cases it may be desirable subsequent to the treating of the clay by means of the said knife device to subject the mass thereby obtained to a further grinding operation in a grinding mill of suitable construction, for instance a roller, mill, ball mill or the like.

The mass obtained from the knife device or from the grinding mill may be conveyed to a storing tank of suitable capacity, if desired provided with an agitator.

An embodiment of an apparatus for carrying out the method according to the invention will be described with reference to the accompanying drawing, wherein

Fig. 1 is a longitudinal sectional view of the apparatus and

Fig. 2 is a vertical cross sectional view of the same, along the line II—II in Fig. 1.

With reference to the drawing 1 is a supply hopper through which the clay is supplied to a container 1', having an outlet 1'' through which the clay is forced by means of a rotating feeding device comprising pug mill knives 2 and a feeding screw 3 driven by means of pulley 10. The outlet 1'' opens into a second container 5, in which the quickly rotating knife device 4 is arranged, in close proximity to the outlet so as to cut the clay fed through the outlet into very thin slices and small particles. The knife device is mounted in the bearings 12, 12 and is driven by means of the pulley 13.

The knife device 4 consists of a plurality, for instance four knives of sickle shape, as more clearly shown in Fig. 2, whereby the cutting is facilitated and the clay particles are caused to slide along the knives and be thrown outwardly, thereby preventing a clogging of the clay to the knives. The cross section of the knives may have any suitable shape, for instance as a segment of a circle, as clearly shown in Fig. 1.

25 The container 5 is provided with a water supply pipe 14, directing a jet of water against the knife device 4. In the embodiment shown the pipe 14 is directed in the plane of the knife device, but may be arranged at any suitable angle.

30 In the container 5 an agitator (not shown) may be provided, preferably driven by the axle of the knife device. From the container 5 the clay mixture is fed through an outlet 6. Preferably the outlet 6 is arranged in a separate compartment 35 in the container 5 opening at or near the bottom of the container as shown by 6' in Fig. 2. From the outlet 6 the clay may be conveyed to a grinding mill 7 with bars or rollers 8, which may consist of pipes filled with concrete, in which mill

40 clay which may not yet have been sufficiently finely divided is further treated so as to produce a satisfactory, even and fine suspension. The grinding mill 7 is carried by and driven by the rotating rollers 11, these rollers preferably being 45 driven by means of a suitable transmission from the main driving source of the apparatus.

The grinding mill 7 is provided with an outlet 9 through which the suspension is discharged and carried directly to the place where it is to be used or to a storing tank or the like.

50 The method according to the present invention also has the advantage as compared with previously known methods that the suspension of clay is obtained as a separate product. This is of 55 advantage in case the clay is available near the

road or where the clay must be brought from a place distant from the place where the gravel is available. Further it is not necessary to bring new gravel to roads where new binding agent only is required. The method further gives the advantage that a new gravel surface more easily may be adhered to an old road base. Also the richness of the suspension easily may be varied according to the requirements in each case.

The method also facilitates obtaining of an even distribution of clay particles with different degrees of cohesion, an important point if there is the question of mixing clays from different sources, or of adding chemicals to the clay.

What I claim is:

1. In an apparatus for the continuous production of aqueous suspensions of clay, especially adapted for use in the stabilization of gravel road surfaces and bases, a container for receiving the clay to be treated, this container having a restricted passage with a substantially unobstructed outlet opening into a second container, and a feeding device in said first-named container for continuously pressing the clay through the said passage and outlet in the form of a relatively dry mass, a rapidly rotating knife device mounted in the said second container in close proximity to the outlet from the first container for rotation in the transverse plane of said outlet, so as to cut the clay passing through the latter into very thin slices and small particles, and means for directing a jet of water against the knife device whereby the clay is wet simultaneously with the cutting thereof, so as to form the desired aqueous suspension and also to aid in freeing any adherent particles from the knife device.

2. In an apparatus for the continuous production of aqueous suspensions of clay, especially adapted for use in the stabilization of gravel road surfaces and bases, a container for receiving the clay to be treated, this container having a restricted passage with a substantially unobstructed outlet opening into a second container, and a feeding device in said first-named container for continuously pressing the clay through the said passage and outlet in the form of a relatively dry mass, a rapidly rotating knife device mounted in the said second container in close proximity to the outlet from the first container for rotation in the transverse plane of said outlet, so as to cut the clay passing through the latter into very thin slices and small particles, and means for directing a jet of water against the knife device whereby the clay is wet simultaneously with the cutting thereof, so as to form the desired aqueous suspension and also to aid in freeing any adherent particles from the knife device.

3. In an apparatus for the continuous production of aqueous suspensions of clay, especially adapted for use in the stabilization of gravel road surfaces and bases, a container for receiving the clay to be treated, this container having a restricted passage with a substantially unobstructed outlet opening into a second container, and a feeding device in said first-named container for continuously pressing the clay through the said passage and outlet in the form of a relatively dry mass, a rapidly rotating knife device mounted in the said second container in close proximity to the outlet from the first container for rotation in the transverse plane of said outlet, so as to cut the clay passing through the latter into very thin slices and small particles, and means for directing a jet of water against the knife device whereby the clay is wet simultaneously with the cutting thereof, so as to form the desired aqueous suspension and also to aid in freeing any adherent particles from the knife device, said knife device comprising a plurality of generally radially extending blades operating in said plane and curved toward their direction of movement in such a manner that the clay particles tend to slide along the blades and to be thrown outwardly.

HOLGER BRUDAL.
